CATHODE RAY TUBE DEFLECTING CIR-
CUITSArthur W. Vance, Haddonfield, N. J., assignor to
Radio Corporation of America, a corporation of
Delaware

Application March 30, 1935, Serial No. 13,815

9 Claims. (Cl. 250—27)

My invention relates to cathode ray tube deflecting circuits and particularly to circuits for supplying to deflecting coils a flow of current having a saw-tooth wave form.

One object of my invention is to provide an improved deflecting circuit for producing a flow of current in cathode ray tube deflecting coils which has a substantially pure saw-tooth wave form.

A further object of my invention is to provide a simplified deflecting circuit which can be synchronized easily and which will supply current having a saw-tooth wave form.

A still further object of my invention is to provide a deflecting circuit having the minimum number of vacuum tubes for supplying current having a substantially pure saw-tooth wave form.

In one of the preferred embodiments of my invention, two electric discharge tubes are employed, the output circuit of one tube being coupled to the input circuit of the second tube through a wave shaping network. The output circuit of the second tube includes a pair of deflecting coils and the voltage appearing across these coils is fed back to the input circuit of the first tube in such phase that the complete circuit is self-oscillatory. The first tube is biased substantially to cut-off, while the second tube is preferably of a larger size which may be biased for operation along the linear portion of its characteristic.

Other objects, features and advantages of my invention will appear from the following description taken in connection with the accompanying drawings, in which

Figure 1 is a circuit diagram of a deflecting circuit embodying my invention;

Figs. 2 and 3 are circuit diagrams of other embodiments of my invention;

Fig. 4 is a characteristic curve of a tube shown in Fig. 1; and

Figs. 5 and 6 are curves which are referred to in explaining the operation of my improved deflecting circuit.

Referring to Fig. 1, the deflecting circuit includes two electric discharge tubes 1 and 2 which may be of the three electrode type as illustrated. Preferably, the second tube has a considerably greater power rating than the first tube, the tube being of the 245 type and the other tube being of the 227 type in the specific circuit being described.

The first tube has an indirectly heated cathode 3, a control grid 4 and a plate 6. The plate 6 is supplied with a suitable positive potential

through an impedance unit such as a resistor 7 from any suitable source of potential.

The input circuit of the tube 1 includes a grid resistor 8 and a self-biasing resistor 9, the self-biasing resistor being shunted by a condenser 11 having a suitable capacity value.

The second tube 2 comprises a directly heated cathode 12, a control grid 13 and a plate 14. The cathode 12 is supplied with current from any suitable source (not shown), the current source and the cathode being shunted by a potentiometer 16.

The input circuit of the tube 2 includes a grid resistor 17 and a self-biasing resistor 18 which is connected to the midpoint of the potentiometer 16 in accordance with well known practice. The self-biasing resistor 18 is shunted by a condenser 19 which has a capacity of the proper value to maintain a substantially steady bias on the control grid 13.

The plate 14 of the tube 2 is supplied with a positive potential through an impedance unit such as a choke coil 21 from a suitable voltage source (not shown). A pair of deflecting coils of a cathode ray tube (not shown) are indicated at 22, these coils being coupled to the output circuit of the tube 2 through a blocking condenser 23 and a conductor 24.

The output circuit of the first tube 1 is coupled to the input circuit of the second tube 2 through a wave shaping network 25 which comprises a resistor 26 and a condenser 27 connected in series. This network is connected across the output circuit of the first tube through a coupling condenser 28. The input circuit of the second tube is connected across the network 25 through a variable tap 29 on the resistor 26.

It will be evident that if a positive voltage impulse is impressed upon the grid 4 of the first tube, a positive voltage impulse will appear in the output circuit of the second tube 2. Therefore, by coupling the output circuit of the second tube to the input circuit of the first tube the deflecting circuit is made self-oscillatory. In the preferred embodiment, this coupling is made through a coupling condenser 31 but it should be understood that this coupling may be made through a transformer if desired.

One of the features of my invention is that the first tube 1 is normally biased substantially to plate current cut-off while the second tube 2 is normally biased to operate along substantially the linear portion of its characteristic. The characteristic of the first tube is shown by the curve 32 in Fig. 4, the dotted line 33 indicating

the bias point about which the tube works. It will be apparent that if the grid 4 is swung positive, there will be a large flow of plate current, while if the grid 4 is swung negative, there will be only a small plate current flow.

Before explaining the manner in which the deflecting circuit oscillates to produce a flow of saw-tooth current through the deflecting coils 22, it may be pointed out that if the deflecting coils 22 are substantially purely inductive, (which they are in the preferred circuit) when current having a saw-tooth wave form flows through them, the voltage appearing across the coils will have the rectangular wave form shown by the curve 34 in Fig. 5. If a voltage having this wave form is impressed upon the input circuit of the first tube 1, a voltage having the same wave form will be impressed across the wave shaping network 25. This voltage will produce a current flow through the resistor 26 and condenser 27 whereby a voltage impulse having a rectangular wave form will appear across the resistor 26 as indicated by the curve 36 in Fig. 6 and a voltage having a saw-tooth wave form will appear across the condenser 27 as indicated by the curve 37 in Fig. 6. As explained in my Canadian Patent No. 346,227, issued November 20, 1934, by moving the tap 29 along the resistor 26 to obtain the proper ratio of rectangular voltage to saw-tooth voltage, current having a substantially pure saw-tooth wave form will flow through the deflecting coils 22. If the plate impedance of the tube 2 is low, only a small saw-tooth component is required in the voltage impressed upon the grid 13 of that tube. However, if the plate impedance of the tube is high, as in the case of a screen grid tube, the saw-tooth component which is required may be much greater than the impulse component.

Referring now to the manner in which the circuit oscillates, if we assume a small change in a decreasing direction of the plate current of the second tube 2, this will swing the grid 4 of the first tube positive through the coupling condenser 31. This positive voltage, of course, is put on the grid 4 as a result of the charging current of the coupling condenser flowing through the grid resistor 8. As a result of the positive voltage on the control grid 4, there will be an increase in the plate current of the tube 1 whereby there will be a less positive or a more negative voltage applied to the control grid 13 of the second tube, thus further decreasing the plate current of that tube. This further decrease in plate current applies a still more positive potential to the grid 4 of the first tube through the coupling condenser 31. It will be seen that this is a cumulative action and that it will continue until either the plate current of the second tube can decrease no more or until the plate current of the first tube can increase no more, probably the latter in this particular circuit where the second tube has a much greater power rating than the first tube.

As the first tube reaches the condition of plate current saturation (or the second tube the condition of cut-off), less charging current is fed through the coupling condenser 31 and through the grid resistor 8 whereby less positive voltage is applied to the grid 4. This causes the grid 13 of the second tube to become less negative whereby the plate current of the tube 2 begins to increase.

As a result a negative voltage is applied through the coupling condenser 31 to the grid 4. This causes the grid 13 of the second tube to become more positive, and the plate current of the tube 75 is further increased.

This action is also cumulative and continues either until the plate current of the first tube can decrease no more or until the plate current of the second tube can increase no more, probably the former condition because of the high bias on the first tube.

From the above description it will be seen that the voltage which appears across the deflecting coils 22 is impressed upon the grid 4 of the first tube and that, if there were no resistance in the deflecting coil circuit, the rectangular voltage impulse appearing across the deflecting coils (as the result of saw-tooth current flowing therethrough) would have exactly the wave form required for the voltage which is to be impressed upon the grid 13 of the second tube. Since the deflecting coil circuit includes the plate resistance of the second tube 2 as well as a certain amount of resistance in the coils, the wave shaping network 25 is essential because otherwise it would be impossible to give the deflecting coil current a saw-tooth wave shape; and, consequently, the voltage appearing across the deflecting coils 22 would not have the rectangular wave shape shown in Fig. 5. Furthermore, even if it did have this rectangular wave shape, the voltage impressed upon the grid 13 of the second tube would not have the proper wave form since the required saw-tooth component would be missing.

From the above remarks it will be apparent that in order to obtain a voltage across the wave shaping network 25 which consists of a rectangular component and a saw-tooth component, a rectangular voltage wave must be impressed on the grid of the first tube, and that a voltage having this wave form can be obtained from the output circuit of the second tube only by passing a substantially pure saw-tooth current through the deflecting coils, the wave shape of the deflecting coil current, in turn, being dependent upon the voltage obtained across the wave shaping network. It might appear that with one unit in the circuit dependent upon another unit in this manner it would be impossible to obtain a satisfactory circuit adjustment. Experience has shown, however, that it is not especially difficult to so adjust a circuit of this character that the current flowing through the deflecting coils will have a perfect saw-tooth wave form. To adjust the circuit, the coupling condenser 31 is adjusted to a capacity value such that the circuit oscillates at approximately the desired frequency. Then the variable tap 29 is moved along the resistor 26 of the wave shaping network until the wave form of the deflecting coil current is made as close to a saw-tooth as possible. This causes a slight change in the frequency of oscillation which is corrected for by readjusting the coupling condenser 31. The change in the capacity of the coupling condenser also causes a slight change in the wave form of the deflecting coil current. The adjustment of the wave shaping network is again changed to produce a still more perfect saw-tooth current. After several such circuit adjustments, the current passing through the deflecting coils has a perfect saw-tooth wave form.

The reason that the positive voltage impulse impressed upon the grid 4 of the first tube through the coupling condenser 31 is of much shorter duration than is the negative voltage impulse, may be explained by the fact that the coupling condenser 31 cannot transfer any direct current energy. Therefore, the energy in the positive cycle must equal that in the negative cycle, or expressing in a different way, the area of a positive im-

5 pulse must equal the area of a negative impulse as indicated in Fig. 5. Since the first tube is biased substantially to cut-off, a positive voltage impressed upon the grid causes a much greater change in voltage in the output circuit of the second tube than does a negative voltage of equal magnitude. For the areas under the positive and negative cycles to be equal, the time taken by the negative swing must be considerably longer than the time taken by the positive swing.

10 The difference in the duration of the positive and negative cycles may also be explained if we assume that the positive impulse fed back to the grid 4 of the first tube causes the coupling condenser 31 to charge to a voltage more than sufficient to block the tube 1 at the end of the positive impulse. The positive impulse lasts for the time required for the deflecting coils 22 to discharge their stored energy through the second tube 2.

15 The first tube remains blocked until the charge on the coupling condenser 31 has had time to leak off through the grid resistor 8 sufficiently to raise the grid bias above the cut-off value. This determines the comparatively long duration of the negative cycle.

20 It should be understood that it is difficult to determine the exact operation of a circuit of this character, and that, for this reason, I do not wish to be limited to any particular theory of operation.

25 The operation of the circuit as described above depends upon using a coupling condenser 31 which has sufficiently small capacity. However, if a coupling condenser of large capacity is used, a capacity so large as to have a very small alternating current impedance at the frequencies involved, the same result can be obtained by giving the condenser 11 shunting the self-bias resistor 9 a sufficiently small capacity. If this embodiment of my invention is employed, the circuit is adjusted the same as previously described except the capacity of the shunting condenser 11 is adjusted instead of the capacity of the coupling condenser 31.

30 When the capacity values indicated in Fig. 1 for condensers 11 and 31 are employed, the frequency of oscillation is determined mainly by the capacity of the coupling condenser 31 and to a less extent by the capacity of the condenser 11.

35 The above-described deflecting circuit was utilized for generating saw-tooth deflecting waves for the comparatively high frequency horizontal deflection in a television receiver. The circuits shown in Figs. 2 and 3 were designed for providing the comparatively low frequency saw-tooth waves required for vertical deflection.

40 Referring to Fig. 2, the deflecting circuit comprises two screen grid tubes 41 and 42 connected as a direct current amplifier. The first tube 41 has an indirectly heated cathode 43, a control grid 44, a screen grid 46 and a plate 47. A positive potential is supplied to the plate 47 through a plate resistor 48 from a voltage divider 49. The screen grid 46 is supplied with a suitable positive potential.

45 The input circuit of the tube 41 includes a grid resistor 51 and a biasing resistor 52, the grid end of the biasing resistor 52 being connected to the negative terminal of the source of biasing voltage (not shown).

50 The second tube 42 includes an indirectly heated cathode 53, a control grid 54, a screen grid 56 and a plate 57. The plate 57 is supplied with a positive potential through a choke coil 58 and a resistor 59 from the voltage divider 49. The

5 screen grid 56 is supplied with a lower positive potential from a point on the voltage divider 49.

10 The control grid 54 is connected through a conductor 61 directly to the plate 47 of the first tube. The cathode 53 is connected through a resistor 62 to the cathode 43 of the first tube whereby the flow of plate current through the resistor 62 maintains the cathode 53 positive with respect to the control grid 54. The resistor 62 is shunted by a suitable by-pass condenser 63.

15 A wave shaping network 64, similar to the one previously described and comprising a resistor 66 and a condenser 67, is connected across the input circuit of the second tube 42.

20 Cathode ray tube deflecting coils indicated at 68 are connected across the output circuit of the tube 42, the upper terminal of the coils being connected to the plate 57 through a coupling condenser 69 and the other terminal of the coils being connected to the cathode 53 through a conductor 71.

25 The output circuit of the second tube 42 is coupled to the input circuit of the first tube 41 through a coupling condenser 72, this condenser having one plate connected to the junction point 25 of the inductance coil 58 and the resistor 59 and having the other plate connected to the control grid 44.

30 In the particular circuit illustrated, synchronizing impulses are applied through a resistor 73 and a condenser 74 to the plate 47 of the first tube. A condenser 76 is connected between the plate end of the resistor 73 and ground so that it, in conjunction with the resistor 73, separates vertical synchronizing impulses from horizontal synchronizing impulses. In this circuit, as in the circuit shown in Fig. 1, the deflecting circuit may be synchronized by impressing the synchronizing impulses upon either the plate or the grid of the first tube. The operation of the circuit shown in Fig. 49 2 is substantially the same as that of the circuit previously described.

35 Referring to the circuit shown in Fig. 3, it differs from the circuit shown in Fig. 1 mainly in that different circuit constants are employed in order to make the circuit oscillate at the lower vertical deflecting frequency. The circuit includes a screen grid tube 77 and a three element tube 78. The screen grid tube 77 has a cathode 79, a control grid 81, a screen grid 82 and a plate 83.

40 The plate 83 is supplied through a resistor 84 with a positive potential from a suitable voltage source. The input circuit of the tube 77 includes a grid resistor 86 and a self-biasing resistor 87, the self-biasing resistor being shunted by a condenser 88 which, as stated in connection with Fig. 1, may have a large capacity value if a small coupling or feed-back condenser is employed, but which must have a comparatively small capacity value if the coupling condenser has a large capacity.

45 The second tube 78 includes a cathode 89, a control grid 91 and a plate 92. The plate 92 of the second tube is supplied through a choke coil 93 with a positive voltage from a suitable voltage source. The input circuit of the tube 78 includes a grid resistor 94 and a suitable biasing source such as a biasing battery 96.

50 The output circuit of the first tube 77 is coupled to the input circuit of the tube 78 through a coupling condenser 97. In this embodiment of the invention, a wave shaping network 98 comprising a resistor 98 and condenser 99 in series are connected across the output electrodes of the

first tube 77. It will be noted that in this circuit the coupling condenser 97 is located between the wave shaping network 95 and the grid 81 of the second tube, instead of between the wave shaping network and the plate of the first tube as in Fig. 1. Either arrangement gives satisfactory operation.

Cathode ray tube deflecting coils indicated at 101 are connected through a coupling condenser 102 and a conductor 103 across the output electrodes of the second tube 78. If desired, they may be shunted by a resistor 104 for the purpose of improving the efficiency of the circuit as described and claimed in my copending application, Serial No. 741,230, filed August 24, 1934, and assigned to the same assignee as this application. When using the particular circuit illustrated, it was found desirable to shunt the coils 101 by a small by-pass condenser 106 for the purpose of eliminating certain undesirable transients in the saw-tooth wave passed through the deflecting coils.

As in the circuit shown in Fig. 1, the output circuit of the second tube 78 is coupled to the input circuit of the first tube 77 through a coupling condenser 107, one plate of the coupling condenser being connected to the upper terminal of the deflecting coils 101 and the other plate of the condenser being connected to the control grid 81 of the first tube. In any of the circuits described, satisfactory synchronization may be obtained by impressing synchronizing impulses upon either the grids or the plates of either the first tube or the second tube.

It will be understood that the synchronizing voltage impulse should be impressed upon a tube electrode in phase with, that is, with the same polarity as, the voltage appearing on said plate due to the self-oscillation of the circuit. The operation of the circuit shown in Fig. 3 as an oscillator for producing a flow of saw-tooth current through the deflecting coils is substantially the same as that of the circuit shown in Fig. 1.

On the drawings the values of the circuit elements are indicated in ohms, megohms, microfarads, henrys, and number of turns.

From the foregoing description it will be seen that many modifications may be made in my invention without departing from the spirit and scope thereof and I desire, therefore, that only such limitations shall be placed thereon as are necessitated by the prior art and are set forth in the appended claims.

I claim as my invention:

1. In combination, a cathode ray tube deflecting coil having substantial inductance, an electric discharge tube having an input circuit and an output circuit, a second electric discharge tube having an input circuit and an output circuit, the output circuit of said second tube being coupled to said coil, a wave shaping network, means for coupling the output circuit of said first tube to the input circuit of said second tube through said network, and means for coupling the output circuit of said second tube to the input circuit of said first tube in such phase as to produce oscillations, the wave form of said oscillations being determined in part by the inductance of said deflecting coil, said first tube being biased substantially to plate current cut-off, and said network being so designed and adjusted as to cause a saw-tooth current to flow through said deflecting coil.

2. The invention according to claim 1 characterized in that said network consists of a resistor and capacitor in series connected across the input circuit of said second tube.

3. In apparatus of the class described, an electric discharge tube having an input circuit and an output circuit, a second electric discharge tube having an input circuit and having an output circuit which is substantially purely inductive, a wave shaping network, means for coupling the output circuit of said first tube to the input circuit of said second tube through said network, and means for coupling the output circuit of said second tube to the input circuit of said first tube in such phase as to produce oscillations, said network including means for producing a voltage wave having an impulse component and a saw-tooth component. 5

4. The invention according to claim 3 characterized in that said network includes a resistor and condenser in series connected in shunt to the input circuit of said second tube. 10

5. In combination, an electric discharge tube having an input circuit and an output circuit, a second electric discharge tube having an input circuit and an output circuit, a cathode ray tube deflecting coil having substantial inductance, said coil being coupled to said second output circuit, a wave shaping network, said first output circuit being coupled to said second input circuit through said network, and means for coupling said second output circuit to said first input circuit whereby oscillations are produced, the wave form of said oscillations being determined in part 30 by the inductance of said deflecting coil, said network being so designed that in response to a rectangular impulse being impressed upon said first input circuit there appears across said network a voltage having a rectangular component and a 35 saw-tooth component. 25

6. The invention according to claim 5 characterized in that the output circuit of said first tube includes a plate resistor connected in series with a source of plate potential, and further 40 characterized in that said network consists of a resistor and condenser in series and connected in shunt to said plate resistor and said source. 45

7. In apparatus of the class described, an electric discharge tube having an input circuit and an output circuit, a second electric discharge tube having an input circuit and having an output circuit which is substantially purely inductive, a wave shaping network, means for coupling the output circuit of said first tube to the input circuit of said second tube through said network, and means for coupling the output circuit of said second tube to the input circuit of said first tube in such phase as to produce oscillations, said network including means for producing a voltage 55 wave having a saw-tooth component. 50

8. In apparatus of the class described, an electric discharge tube having an input circuit and an output circuit, a second electric discharge tube having an input circuit and having an output circuit which is substantially purely inductive, a wave shaping network, means for coupling the output circuit of said first tube to the input circuit of said second tube through said network, and means for coupling the output circuit of said second tube to the input circuit of said first tube in such phase as to produce oscillations, said network including means for producing a voltage 65 wave having a rectangular impulse component. 60

9. In combination, an electric discharge tube 70 having an input circuit and an output circuit, a second electric discharge tube having an input circuit and an output circuit, a cathode ray tube deflecting coil having substantial inductance, said coil being coupled to said second output circuit, 75

a wave shaping network, said first output circuit being coupled to said second input circuit through said network, and means for coupling said second output circuit to said first input circuit whereby oscillations are produced, the wave form of said oscillations being determined in part by the inductance of said deflecting coil,

said network being so designed that in response to a rectangular impulse being impressed upon said first input circuit there appears across said network a voltage having the proper wave shape to produce a flow of saw-tooth current through said deflecting coil.

ARTHUR W. VANCE.
